UNITED STATES PATENT OFFICE.

JOHN M. GAMBLE, OF BURLINGTON, IOWA.

SELF-LOCKING TICKET-WINDOW CLOSURE.

970,912.

Specification of Letters Patent. Patented Sept. 20, 1910.

Application filed December 31, 1909. Serial No. 535,871.

To all whom it may concern:

Be it known that I, JOHN M. GAMBLE, a citizen of the United States, residing at Burlington, in the county of Des Moines and State of Iowa, have invented certain new and useful Improvements in Self-Locking Ticket-Window Closures; and I do hereby declare the following to be a full, clear, and exact description of the invention, such as will enable others skilled in the art to which it appertains to make and use the same.

This invention relates to improvements in self-locking ticket window closures, and has for an object the arrangement of improved means adapted to fit into a ticket window for normally closing the same.

Another object of the invention is the arrangement of improved means for normally closing a ticket window but adapted to automatically open on being released.

A further object of the invention is the arrangement in a ticket window, of a closure therefor and a movable gate arranged to be automatically opened when released.

With these and other objects in view the invention comprises certain novel constructions, combinations and arrangement of parts as will be hereinafter fully described and claimed.

In the accompanying drawings: Figure 1 is a perspective view of one embodiment of the invention shown in position. Fig. 2 is a section through Fig. 1, approximately on line 2-2. Fig. 3 is a front view of the structure shown in Fig. 1 with the front plate removed, the same being shown on a reduced scale. Fig. 4 is an enlarged fragmentary sectional view showing the catch and pivotal securing means therefor.

In constructing the window ticket slide or closure embodying the invention a pair of plates are connected but spaced apart by suitable washers sufficiently for accommodating the thickness of the window to which the closure is to be applied, so that the edge of each plate will overlap the opening in the window when in position, and thereby hold the closure in place. On one of the plates is mounted a pair of slides between which is positioned a sliding gate having the edges fitting into said slides, normally held elevated by a retractile spring connected therewith, and with the plate carrying the slides. A spring pressed catch is pivotally mounted to the same plate which carries the guides, and is arranged to have the lower

end thereof engage the upper edge of the gate for holding the same lowered or depressed when moved to that position manually against the action of its retractile spring. A spring is provided for normally holding said catch in engagement with the gate for maintaining the gate in a depressed position. When it is desired to open the gate all that is necessary is to press upon the upper end of the catch which will cause the lower end thereof to move from above the gate. This will permit the retractile spring to immediately elevate the gate, and thus present an opening through which articles may be passed.

In order that the invention may be more clearly understood an embodiment of the same is shown in the accompanying drawings, in which 1 indicates a ticket window having the usual opening formed therein. In the opening in the ticket window 1 are positioned plates 2 and 3. The plates 2 and 3 are held in proximity by suitable bolts 4, but are also held spaced apart by washers 5, preferably of some elastic or yielding material, as rubber. When placing the plates 2 and 3 in position, plate 3 is placed upon the outside of the window, and the plates are drawn toward each other until the same engage the window 1, the yielding washers 5 permitting such movement. Each of the plates is formed with a cut out portion 6 which registers when the plates are in position for forming a restricted opening through which articles, as for instance money, may be passed. Secured to plate 2 are slides 7 and 8 which guide gate 9 in its reciprocating movement. Gate 9 is formed with a main body portion 10 designed to close the opening formed by cut away portions 6-6, and a thumb member 11 which is designed to be pressed manually for lowering the gate. The upper end of the gate is formed with a turned over portion 12 which is engaged by a retractile spring 13. Retractile spring 13 is secured at 14 to plate 2 and is designed to be stretched when gate 9 is in its lowered position, as shown in Fig. 2, so as to move the gate upward to the position shown in Fig. 1, and maintain the same in that position when the gate has been released. Plate 2 is formed with a cut out portion 15 which accommodates the hook end 16 of a pivotally mounted latch 17. The hook end 16 is designed to move inward under the action of spring 18, and engage

the upper surface of extension 12 when gate 9 has been lowered, so as to hold the gate in its lowered position. When it is desired to open gate 9 the upper end of latch 17 is 5 pressed inward toward plate 2, as shown in dotted lines in Fig. 2. This will cause the hook end 16 to move from above extension 12, and permit retractile spring 13 to elevate the gate. The latch 17 is provided with a 10 substantially arc-shaped portion 20, through which a retaining pin 21 is passed formed with a substantially arc-shaped head 22 for comparatively loosely holding the latch in position, so as to permit a free pivotal movement thereof.

What I claim is:

1. In a device of the character described, a closure formed with an opening therein, a sliding gate for closing said opening, 20 resilient means for normally holding said gate open, and pivotally mounted means for holding said gate closed against the action of said resilient means.

2. In a device of the character described, 25 a closure proper formed with an opening therein, a sliding gate therefor, a spring for normally moving said sliding gate to an open position, and a catch for holding said gate closed when moved to a closed 30 position.

3. In a device of the character described, a closure proper formed with an opening therein, a sliding gate for normally closing said opening, means for holding said gate 35 in its closed position, and a retractile spring for opening said gate when said last mentioned means has been released.

4. In a device of the character described, a closure proper formed with an opening, 40 a gate for said opening, a retractile spring for tending at all times to hold said gate open, and a catch for holding said gate closed against the action of said spring after the same has been manually closed.

45 5. In a device of the character described,

a closure proper formed with an opening, a gate for said opening formed with a thumb member adapted to be manually engaged for closing the gate, a catch for normally holding the gate closed, and a spring for opening 50 the gate when said catch has been released.

6. In a device of the character described, a closure proper formed with an opening, a reciprocatory gate for said opening, a pair of guide ways mounted on said closure 55 proper for guiding said gate in its movement, a retractile spring secured at one end to said closure proper and at the other end to said gate for normally holding said gate open, and a spring pressed catch arranged 60 with a hook-shaped end for engaging the upper edge of said gate for holding the same closed after having been manually moved to a closed position.

7. In a ticket window closure a plurality 65 of spaced plates formed with registering openings, means for holding said plates in proximity, spacing means for preventing the contact of said plates, and a movable gate connected with said plates for normally closing said openings.

8. In a device of the character described, a plurality of spaced plates, resilient cushioning means positioned between said plates, means for securing said plates in 75 proximity passing through said plates and through said cushioning means, said securing means being designed to vary the distance apart of said plates as desired, a gate for said plates, means for normally holding said gate closed, and means for automatically opening said gate when said last mentioned means has been released.

In testimony whereof I affix my signature in presence of two witnesses.

JOHN M. GAMBLE.
